Filed May 3, 1971, Ser. No. 140,005

Term of patent 14 years

Int. Cl. D7—04

U.S. Cl. D11—1

FIG. 1 is a perspective view of a butcher's spinal cord remover showing our new design, the view of the opposite side being substantially similar;

FIG. 2 is a sectional view taken on the line 2—2 in FIG. 1; and

FIG. 3 is a sectional view taken on the line 3—3 in FIG. 1, the view being angularly rotated to emphasize the concavo-convex appearance of the scoop portions of the device.

We claim:

The ornamental design for a butcher's spinal cord remover, as shown and described.
